UNITED STATES PATENT OFFICE.

GEORG H. LYNEN, OF PASSAIC, NEW JERSEY.

APPARATUS FOR USE IN THE MANUFACTURE OF SUPERPHOSPHATE.

1,093,141.

Specification of Letters Patent. Patented Apr. 14, 1914.

Application filed April 9, 1912. Serial No. 759,869.

To all whom it may concern:

Be it known that I, GEORG H. LYNEN, a citizen of the United States, residing at Passaic, in the county of Passaic and State of New Jersey, have invented a new and useful Improvement in Apparatus for Use in the Manufacture of Superphosphate, of which the following is a specification.

This invention relates to apparatus for use in the manufacture of acid or superphosphate and more particularly to apparatus for removing the superphosphate masses from the decomposition chambers or dens.

In the manufacture of superphosphate, the materials which are employed to produce the superphosphate are mixed and dumped into the decomposition chambers in a liquid or semi-liquid condition, and after remaining in these chambers for a period of time, form a cake or mass of more or less solid material. This material has the peculiarity of again becoming liquid or "muddy" if disturbed or agitated in any manner which will cause friction between the particles thereof. Owing to this peculiarity, it has been very difficult to provide satisfactory mechanical means or apparatus for emptying these chambers, and the work has generally been done by manual labor. This method, however, is objectionable owing to the injurious effects on the operatives of the acid fumes in the chamber and is also expensive.

The objects of this invention are to produce an apparatus by means of which a chamber or den can be quickly emptied with the minimum labor and in such a manner as to eliminate as far as possible any stirring or agitation of the material; also to produce an apparatus for this purpose which is of strong, simple and rigid construction so that the parts thereof are well able to resist the strains to which they are subjected owing to the weight of the material, and also the corrosive action of the acid employed in the manufacture of the superphosphate; also to improve the construction of apparatus of this kind in the respects hereinafter specified.

In the accompanying drawings, consisting of three sheets: Figure 1 is a sectional view of a decomposing chamber showing in elevation the apparatus embodying the invention. Fig. 2 is an elevation of a car which forms a part of the apparatus. Fig. 3 is a

sectional plan on line 3—3, Fig. 1, showing the apparatus in plan. Fig. 4 is a cross-sectional elevation thereof on line 4—4, Fig. 3. Fig. 5 is a fragmentary sectional elevation, on an enlarged scale, on line 5—5, Fig. 3. Fig. 6 is a sectional view of knives or cutters of modified construction, for removing the material from the car. Fig. 7 is a sectional plan view of an apparatus of modified construction. Fig. 8 is a sectional elevation thereof on line 8—8, Fig. 7.

Like reference characters refer to like parts in the several figures.

Briefly stated, the apparatus comprises a car which is adapted to be moved into and out of a decomposition chamber or den having walls which are adapted to engage with the sides of the car to form a receptacle into which the material is poured while in a liquid or semi-liquid state. The car is permitted to stand in the chamber or den until the material has become sufficiently solidified, whereupon the car carrying the substantially solid cake is moved out of the chamber to be emptied. Suitable stationary knives or cutters are preferably provided outside of the decomposition chamber, under which the car passes in moving out of the chamber and which are adapted to cut the cake or mass of material on the car and drop the material into suitable hoppers through which it may be fed to the conveyors or other means for removing it.

A represents a decomposition chamber or den, which may be of any usual or suitable construction, having a floor a , walls a' , and a ceiling a'' provided with one or more tubes or conduits a^3 , by means of which the material in liquid state is delivered to the chamber. A tube or ventilating shaft a^4 serves to conduct fumes and gases from the chamber.

a^5 represents a flexible curtain which serves to close the open end of the chamber to prevent the escape of fumes and gases from the chamber. A curtain of any suitable kind, or other suitable closure can be employed. Instead of discharging the material from the tube a^3 onto the floor of the chamber A, as has heretofore been done, a movable support of any suitable construction is provided, which is adapted to be placed under the tube a^3 in the chamber to receive the material, and to be moved out of the chamber to be emptied. This movable support, as shown, is in the form of a car

B which, in order to facilitate the emptying thereof, preferably has only a floor or platform *b* and a rear wall *b'*, which may be secured to the car in any suitable manner. The car body, as shown, is mounted on wheels *b*² adapted to run on track rails *b*³.

The side and front walls which serve to retain the material on the car may be supported in operative relation to or in engagement with the car in any suitable manner. Since great strength is required in these walls, to withstand the pressure thereon due to the weight of the material, the walls are preferably supported in any suitable manner within the chamber.

In the construction shown in Figs. 1-5 the side walls comprise two upright plates C which are movably mounted in the chamber A to move into and out of engagement with the car, the walls being mounted on wheels *c* which run on transverse rails *c'* on the floor of the chamber A and are moved toward and from the car by means of screw-operating devices D. Each of the screw-operating devices shown, see Fig. 5, consists of a screwthreaded sleeve *d* engaging with a screw *d'* secured to the stationary wall *a'* of the chamber A. The sleeve is swiveled at *d*² to a plate or bearing member *d*³ secured to the movable wall, and is provided with suitable handles *d*⁴ for turning it. Any other suitable means could be employed for moving the walls into engagement with the car B.

In order that the tightening of the screw-operating devices may not bend the upper parts of the side walls inwardly, a cross beam D' is preferably provided intermediate of the ends of the chamber. In the construction shown the cross beam is hinged at *d*⁶ in the side walls *a'* of the chamber and is provided with brackets *d*⁶ which are adapted to engage the inner faces of the movable side walls near the upper edge thereof, to prevent the bending in of the side walls. Other means can be employed for this purpose.

The front wall E of the car, in the construction shown, is pivoted at *e* on the side walls *a'* of the chamber A and is adapted to be swung on its pivots into engagement with the car to close the front end thereof, and when it is desired to remove the car from the chamber the front wall can be swung up into a horizontal position (shown by dotted lines in Fig. 1) above the mass of material on the car, so as not to interfere with the passage of the material beneath it. The front wall, as shown, has a base portion *e'* provided with holes for bolts *e*² for rigidly securing the wall in place on the car. *e*³ indicates braces or ribs connecting the wall and the base portion *e'* thereof. *e*⁴, Fig. 1, represents suitable hoisting tackle or other means for raising the front wall.

Any suitable means may be provided for moving the car into and out of the decomposition chamber such, for example, as a chain or cable F, Fig. 1, which is connected at its opposite ends to the car and which passes around a suitable pulley *f*, located at one end of the chamber. The car can be moved into or out of the chamber by drawing the chain in either direction, which is preferably done by a windlass or other suitable device. Stationary shields or plates G are preferably provided between the movable walls and the open side of the chamber, for preventing any material which might crumble off from the cake, from dropping on the floor of the chamber.

When the car, after having been moved into the chamber, is to be filled with the liquid or semi-liquid material, the front wall is first placed in position on the car and the side walls are then pressed tightly into engagement with the edges of the car floor and the front and rear walls. The material is then delivered to the car and when it has become solidified the side walls are moved away from the car, preferably only enough to avoid friction between the walls and the car when the car is being moved out of the chamber. The walls, when in this position, act to prevent any parts of the material, which may break off, from falling on the floor of the chamber. The front wall is then swung into a position to clear the car and the material thereon and the car can then be moved out of the chamber and emptied in any suitable manner. If the car is to be emptied by hand, the front wall need not be made removable, but could be rigidly secured to the car as in the case of the rear wall.

The material can be unloaded from the car in any convenient manner into suitable hoppers or chutes H H, Figs. 1 and 3, which are located at opposite sides of the car and from which the material is discharged to a suitable belt conveyer *h* or other transporting means. Preferably means are provided for automatically unloading the car, consisting, in the construction shown, of a stationary knife or cutter I outside of the decomposition chamber. This cutter is so located relatively to the car, that the car, in moving out of the chamber, will pass under the cutter. The cutter, see Figs. 1 and 3, is wedge or plow-shaped and adapted to cut approximately into the middle of the cake of material on the car, and deflect the two parts of the cake at opposite sides thereof side-wise into the hoppers as the car moves out of the chamber. The material remaining on the car after the point of the cutter reaches the rear wall can be easily shoveled off of the car.

Fig. 6 shows a device of modified construction for removing the material from

the car and which may be employed in place of the cutter I. This device comprises a wedge-shaped cutter K and two pairs of cutters or knives k k and k' k' which are so located at opposite sides of the cutter K, in the path of movement of the cake of material, that each knife will remove a part or slice of the material on the car.

In the modified construction shown in Figs. 7 and 8, the movable side walls, shown in Figs. 1-5, are dispensed with and the chamber is provided with stationary plates L, which are secured to the side walls of the chamber and which converge toward the inner end of the chamber. The sides of the car also converge in the same manner so that the car can be wedged between the plates L to form a tight joint between the floor of the car and the plates L. The front wall E can be placed in position on the car as heretofore described. When the car is to be moved out of the chamber for unloading the same the front wall is swung into its horizontal position and the first part of the outward movement of the car serves to release the car and the material thereon from engagement with the inclined plates L. The car can then be moved out of the chamber A and unloaded as heretofore described.

By means of the apparatus described the amount of agitation and friction to which the material is subjected in emptying the chambers is greatly reduced. The material is moved sidewise off of the car and is subjected to no friction during its movement in the chamber. No labor is required within the chamber except to adjust the movable walls as desired, and the cost of emptying the dens, as well as the time required for this operation, are greatly reduced by the use of this apparatus.

I claim as my invention:

1. The combination with a chamber, of a movable support which is adapted to be moved into and out of said chamber, and walls in said chamber adapted to engage said movable support to form a receptacle therewith, said support being movable relative to said walls into and out of said chamber, substantially as set forth.

2. The combination with a chamber, of a movable support in said chamber, and upright walls in said chamber at opposite sides of said support which coöperate with said support to form a receptacle for the material, said support being movable with the material thereon from between said walls and out of said chamber, substantially as set forth.

3. The combination with a chamber, of a movable support which is adapted to be moved into and out of said chamber, and walls for said support which are movably supported in said chamber and are adapted

to be moved toward the support to form a receptacle for the material and away from the support to free the material, substantially as set forth.

4. The combination with a chamber, of a platform which is adapted to be moved into and out of said chamber, front and side walls for the platform which are movably mounted in said chamber, and means for moving said walls into and out of engagement with said platform, substantially as set forth.

5. In an apparatus for emptying superphosphate chambers, the combination with a chamber, of a platform which is adapted to be moved into and out of said chamber, removable walls for said platform between which material can be poured, and unloading means outside of said chamber underneath, which said platform is adapted to pass and which engage the material on the platform and remove the same from said platform, substantially as set forth.

6. An apparatus for emptying superphosphate chambers comprising a car adapted to be moved into a chamber to be filled with the material while in liquid state, walls for said car located in said chamber and which are adapted to be moved toward said car to form a receptacle for the material, said walls being movable away from the car when the material has become solid, said car being movable relative to said walls out of said chamber for unloading the car, substantially as set forth.

7. In an apparatus for emptying superphosphate chambers, the combination with a chamber, of a car which is adapted to be moved into and out of said chamber, removable walls for the car, and a stationary unloading device outside of said chamber which is adapted to engage the material when the car passes underneath the same and to remove the material laterally from the car, substantially as set forth.

8. The combination with a chamber, of a platform which is adapted to be moved into and out of said chamber, walls for the platform located in said chamber, said platform being movable relatively to said walls, and an unloading device outside of said chamber for removing the material from the car sidewise thereof, substantially as set forth.

9. In an apparatus for emptying superphosphate chambers, the combination of a chamber, of a car which is adapted to be moved into and out of said chamber, removable walls for the car, and a stationary cutter outside of said chamber above the path of movement of the car which is adapted to engage the material on the car for removing the material laterally from the car when the car passes under said cutter, substantially as set forth.

10. The combination of a chamber, of a

- car which is adapted to be moved into and out of said chamber, walls in said chamber for the car, which are adapted to form with the car a receptacle for the material, and a 5. stationary cutter outside of said chamber above the path of movement of the car for removing the material from the car when the car passes under said cutter, substantially as set forth. 40
- 10 11. The combination with a chamber, of a horizontally movable support in said chamber, and movable walls in said chamber which coöperate with said support to form a receptacle for the material, said 45 walls being adapted to be moved away from the material on said support, and said support being movable with the material thereon relative to said walls, substantially as set forth. 50
- 20 12. The combination with a chamber, of a horizontally movable support in said chamber, and upright walls in said chamber at opposite sides of said support, which coöperate with said support to form a receptacle for the material, said walls being adapted to be moved away from said support, and said support being movable with the material thereon from between said walls, substantially as set forth. 55
- 30 13. The combination with a chamber, of a car which is adapted to be moved into and out of said chamber, walls in said chamber adapted to engage with the car, and stationary cutters arranged outside of said 35 chamber above the path of movement of the 60
- car and faces inclined with regard to the direction of movement of the car and which remove the material laterally from the car when the car passes under said cutters, substantially as set forth. 65
14. The combination with a chamber having an open end, of a car which is adapted to be moved into and out of said chamber through said open end, walls for the car which are movably supported in said chamber and are adapted to be moved toward the car to form a receptacle for the material, and away from the car to free the material, and stationary walls in said chamber between said movable walls and said open end 50 of the chamber which are adapted to retain the material on said car when the car is moving out of the chamber, substantially as set forth. 55
15. The combination with a chamber, of a platform movable into and out of said chamber, upright side walls in said chamber which are adapted to engage with said platform, and a movable end wall supported in said chamber and adapted to be moved into 60 engagement with said platform and said side walls to form a receptacle for the material, substantially as set forth. 65

Witness my hand, this 19th day of March, 1913.
